Primary Examiner — Deanna L Pratt(74) *Attorney, Agent, or Firm* — Nancy J. Flint, Attorney at Law, P.A.; Nancy J. Flint, Esq.(57) **CLAIM**

The ornamental design for an entertainment chair, as shown and described.

DESCRIPTION

FIG. 1 is a front perspective view of an entertainment chair showing my new design;

FIG. 2 is a front view showing the entertainment chair;

FIG. 3 is a left side view showing the entertainment chair;

FIG. 4 is a rear view showing the entertainment chair; and,

FIG. 5 is a top view showing the entertainment chair. Right side view not shown is a mirror image of the left side view. Bottom view not shown is not part of the design sought to be patented.
